STARTER GEARING FOR INTERNAL COMBUSTION ENGINES

John J. Sabatini, Elmira, N. Y., assignor to Bendix Aviation Corporation, Elmira Heights, N. Y., a corporation of Delaware

Application July 5, 1955, Serial No. 519,851

7 Claims. (Cl. 74—7)

The present invention relates to starter gearing for internal combustion engines and more particularly to that type in which connection of the starting motor to the engine is effected by acceleration of the starting motor, and disconnection is brought about by self-operation of the engine above a predetermined speed.

In devices of this type where a pinion is traversed into engagement with an engine gear by means of a screw-threaded connection to the motor shaft, there is a substantial amount of kinetic energy stored in the rotating parts prior to completion of the meshing movement, and various forms of yielding driving connection are used to cushion the application of the "deceleration torque" developed by this kinetic energy when the engagement of the pinion is completed.

Cost considerations and space limitations have made the provision of said yielding driving connections a major problem, and the recent adoption of 12-volt starting system for automotive engines involving high torque and very rapid acceleration of the motor have aggravated the problem.

Since the amount of kinetic energy stored in the rotating parts prior to full mesh of the pinion is a function of the amount of free rotation of the starting motor, it is desirable to reduce to a practical minimum the amount of rotation needed to mesh the pinion. There is a limit to the pitch of the threaded connection, however, beyond which traversal of the pinion into initial mesh becomes uncertain.

It is an object of the present invention to provide a novel engine starter gear of the above type incorporating means for meshing the drive pinion with the engine gear responsive to a comparatively small arc of rotation of the starting motor.

It is another object to provide such a device in which the initial meshing movement of the pinion is brought about by a threaded connection, but the meshing movement is completed by an inclined connection of higher pitch than the threaded connection.

It is another object to provide such a device incorporating yielding means for normally holding the inclined connection in retracted position.

It is another object to provide such a device incorporating a yielding buffer for limiting the extension of the inclined connection.

Further objects and advantages will be apparent from the following description taken in connection with the accompanying drawing in which:

Fig. 1 is a side elevation partly broken away and in section of a preferred embodiment of the invention showing the parts in normal or idle position;

Fig. 2 is a view similar to Fig. 1, showing the parts in the positions assumed when the pinion has started into mesh with the engine gear;

Fig. 3 is a view similar to Fig. 1 showing the parts in cranking position; and

Fig. 4 is a sectional detail taken substantially on the line 3—3 of Fig. 1.

2

In Fig. 1 of the drawing there is illustrated a power shaft 1 on which a hollow sleeve 2 is fixedly mounted in any suitable manner as indicated at 3. The sleeve 2 is formed with straight splines for a portion of its length as shown at 4, and a driving overrunning clutch member 5 is slidably and non-rotatably mounted thereon, being normally urged against a lock ring 6 seated in a groove 7 in the sleeve by means of a mesh-enforcing spring 8 seated in a counter-bore of a thrust member 9 fixed in any suitable manner on the end of the sleeve 2.

A hollow screw shaft 11 is slidably journaled on the sleeve 2 and is formed on one end with overrunning clutch teeth 12 cooperating with similar teeth 13 on the clutch member 5. A stop member 14 is mounted on the other end of the sleeve 2, being maintained thereon by a lock ring 15 seated in a groove 16 in the sleeve, and a spring washer 17 located between the stop member 14 and the adjacent end of the screw shaft 11 normally maintains the overrunning clutch teeth 12, 13 in engagement.

20 A pinion 18 is slidably journaled on the power shaft 1 for movement into and out of mesh with a gear 19 on the engine to be started. Means for actuating the pinion from the screw shaft 11 is provided comprising a control nut 21 threaded on the screw shaft and a barrel member 25 indicated generally by the numeral 22 for connecting the control nut to the pinion. Barrel member 22 is composed of two parts 23 and 24 in order to facilitate assembly of the drive, the two parts being anchored together by means of radial lugs 25 on the part 23 which engage in slots 26 in the part 24, and are retained therein by a lock ring 27. The part 23 of the barrel is rigidly mounted on the pinion 18 as indicated at 28, and the part 24 of the barrel is provided with inclined slots 29 formed to slidably receive radial projections 31 of the control nut 21, the inclination of the connection 29, 31 being in the same direction or "hand," but substantially steeper than the pitch of the threads of the screw shaft 11.

Means is provided for normally maintaining the projections 31 at the right hand end of slots 29 as shown in 40 Fig. 1, whereby the inclined connection is in retracted position. This means is preferably in the form of a compression spring as shown at 32, or may, if preferred, be in the form of a ring of elastically deformable material such as rubber, interposed between a terminal flange 33 on the barrel member 24 and a thrust washer 34 mounted on the control nut 21. A plurality of dished spring washers 35 are seated on the control nut between the projections 31 thereof and the thrust washer 34, said washers being maintained under initial compression by a lock ring 36 seated in a groove on the control nut.

The idle position of the control nut 21 on the screw shaft is defined by the ends 37 of the threads of the screw shaft. In order to prevent the control nut from drifting away from idle position, one or more of the threads on the screw shaft 11 are cut down to provide an inclined shoulder 40, and a spring pressed detent 38 (Fig. 4) is arranged to engage said shoulder to resist such drifting movement.

Means are provided for holding the pinion 18 in mesh with the engine gear 19 until the engine is operating at a predetermined speed. For this purpose a notch 39 is formed in the screw shaft to provide a shoulder 41 so positioned as to receive the detent 38 when the pinion is meshed with the engine gear and thereby prevent detaching movement of the control nut until the detent is withdrawn by centrifugal force.

In operation, starting with the parts in the positions as shown in Fig. 1, acceleration of the power shaft 1 by the starting motor, not illustrated, causes the screw shaft 11 to be rotated by the clutch member 5 whereby the control nut 21 is traversed in the meshing direction until its movement is arrested by the stop member 14, a thrust

washer 42 being preferably interposed. At this time, the teeth of the pinion 18 have entered into initial meshing relation with the engine gear 19 as shown in Fig. 2. Further rotation of the power shaft causes the screw shaft 11 to be moved backward, compressing the mesh-enforcing spring 8 until the clutch member 5 engages the thrust member 9 whereby its longitudinal movement is arrested. The torque transmitted from the screw shaft to the control nut then becomes operative to cause the inclined connection 29, 31 between the control nut and barrel member 24 to traverse the barrel and pinion assembly to the fully meshed position, compressing the spring 32 in the process as shown in Fig. 3. The final meshing movement of the pinion and barrel assembly brings the shoulder 43 of the barrel member 24 into engagement with the thrust washer 34, whereby the shock of engagement is cushioned by compression of the spring washers 35.

If, during the meshing movement, tooth abutment should occur between the pinion 18 and engine gear 19, the screw shaft and clutch member 5 are permitted by the mesh enforcing spring 8 to move backward and thereby provide time for torque to be built up to index the pinion teeth into proper registry with the tooth spaces of the engine gear.

It will be noted that since the traversing action of the screw shaft on the control nut is called upon only to secure initial engagement of the pinion with the engine gear, only a small amount of rotation of the power shaft 1 is needed, and since the completion of the meshing movement is brought about by the high pitch inclined connection 29, 31 between the control nut and barrel, the total rotation of the power shaft to secure meshing of the pinion is comparatively small and the kinetic energy stored up in the rotating parts is correspondingly reduced, thus minimizing the shock of engagement.

Although but one form of the invention has been shown and described in detail it will be understood that changes may be made in the design and arrangement of the parts without departing from the spirit of the invention.

I claim:

1. In an engine starter drive a power shaft, a sleeve fixed thereon, a screw shaft slidably journaled on the sleeve, means connecting the screw shaft to rotate with the sleeve, a pinion slidably journaled on the power

shaft for movement into and out of mesh with a gear of the engine to be started, a control nut threaded on the screw shaft, means limiting the travel of the control nut on the screw shaft, means for actuating the pinion from the control nut including a barrel member fixed at one end to the pinion and having an inclined connection with the control nut of the same direction as the threads of the screw shaft but of steeper inclination, and yielding means for resisting meshing movement of the pinion and barrel with respect to the control nut.

2. An engine starter drive as set forth in claim 1 including further a yielding abutment limiting the meshing movement of the pinion and barrel with respect to the control nut.

3. An engine starter drive as set forth in claim 1 in which the means for connecting the screw shaft to rotate with the sleeve comprises a driving overrunning clutch member splined on said sleeve, and yielding means urging said clutch member and screw shaft into clutching engagement.

4. An engine starter drive as set forth in claim 3 including further means for limiting the travel of the clutch member on the sleeve.

5. An engine starter drive as set forth in claim 3 in which the means for limiting the travel of the control nut on the screw shaft comprises a stop member on the sleeve, and the yielding means for urging the screw shaft and clutch member into engagement comprises a compression spring between said stop member and the screw shaft.

6. An engine starter drive as set forth in claim 5 including further yielding means urging the overrunning clutch member toward the screw shaft, and means for limiting the expansion of said yielding means.

7. An engine starter drive as set forth in claim 3 including further a centrifugally released latch on the control nut positioned to engage a shoulder on the screw shaft and prevent demeshing movement of the control nut until the pinion and barrel assembly has attained a predetermined rotational speed.
